UNITED STATES PATENT OFFICE.

WILLIAM F. ARZINGER, OF JERSEY CITY, NEW JERSEY.

BOTTLE-FILLING AND FLUID-MEASURING MACHINE.

1,071,682.

Specification of Letters Patent. Patented Sept. 2, 1913.

Application filed December 29, 1911. Serial No. 668,413.

To all whom it may concern:

Be it known that I, WILLIAM F. ARZINGER, a citizen of the United States, and a resident of Jersey City, in the county of Hudson and 5 State of New Jersey, have invented a new and Improved Bottle-Filling and Fluid-Measuring Machine, of which the following is a full, clear, and exact description.

My invention relates to filling machines 10 and it has for its object to provide one with a member having a filling chamber with inlet and outlet ports, and valves for commanding the ports, and mounted yielding- 15 ly on a valve spindle, so that when the member having the filling chamber which carries a nozzle, is moved down relatively to the spindle, the inlet port will be closed, and the outlet port will be subsequently opened, to permit the fluid to flow through the nozzle 20 into the bottle.

Another object of the invention is to connect a reservoir with the filling chamber, and to provide the reservoir with an adjustable sleeve, in which a tube secured to 25 the float travels, the float fitting the sides of the reservoir and preventing an additional amount of fluid flowing into the reservoir when the movement of the float is stopped by contact with the sleeve.

Still other objects of the invention will 30 appear in the following complete specification in which the preferred form of the invention is disclosed.

In the drawings similar characters of reference indicate corresponding parts in all the views, in which Figure 1 is an elevation of the machine, parts being shown in section; Fig. 2 is a sectional view on the line 2-2 of Fig. 1; Fig. 3 is a sectional view 40 similar to that shown in Fig. 2, but with both ports in the filling chamber closed; and Fig. 4 is a sectional view showing the filling chamber with the inlet port closed, and the outlet port opened.

By referring to the drawings it will be seen that mounted on a frame 5 there are two standards 6, sleeves 7 being disposed on the standards, and being held in predetermined positions by the set screws 8. The 50 sleeves 7 have flanges 9, on which is disposed a transverse stop member 10, this stop member being held on the flanges 9 by the bolts 11. A transverse member 12 is mounted for sliding on the standards 6, this trans- 55 verse member 12 having opening 13, in which the studs 14 on the heads 15 are dis-

posed. Washers 16 are mounted on the studs 14, and the transverse member 12, the washers 16 being engaged by the heads of bolts 17, which extend through openings in 60 the washers and engage the studs 14. The heads 15 are screwed on the filling members 18, each of these filling members 18 having a filling chamber 19, with heads 20 and 21. In the head 20 there is an inlet port 22, and 65 in the head 21 there is an outlet port 23. In the side of each of the filling members 18 there is a threaded opening 24, in which meshes a thread on the pipe 25, the pipe 25 communicating with the filling member 18 70 above the head 20, and the port 22. There is also a second opening 26 in the side of each of the filling members 18, in which is disposed a pipe 27, this pipe 27 affording an outlet from the outlet port 23. The bottom 75 of the filling members 18 have elongated bearings 28, in which are disposed the valve spindles 29, the lower terminals 30 of the valve spindles 29 resting on the stops 10. Mounted for sliding on each of the valve 80 spindles 29 there are two valves 31 and 32, there being a collar 33 secured to the valve spindle between the valves and a spring 34 being mounted on the valve spindle between the collar 33 and the valve 32, and a spring 85 35 being mounted on the valve spindle 29, between the collar 33, and the valve 31. Both of these springs are disposed in the filling chamber 19, the upper terminal of the valve spindle extending through the outlet port 23, to permit of this. 90

On the upper terminal of the valve spindle 29 there is a stop 36, which prevents the valve 32 from slipping from the valve spindle 29. A collar 37 is secured to the valve 95 spindle 29, below the valve 31, and this collar 37 is normally disposed in a recess 38 in the bearing 28. The springs 39 serve to hold the transverse member 12 upward and with it the filling members 18 with their 100 chambers 19; and the springs 39 which are mounted on the valve spindles 29 between the packing nuts 40 at the bottom of the bearings 28 and the nuts 41 which mesh with the threads 42 on the lower terminals 30 of the valve spindles 29 serve to hold the valve 105 spindles 29 down relatively to the filling members 18 with the valves in the position shown in Fig. 2 of the drawings. It will thus be seen that, by adjusting the nut 41 110 the action of the spring 39 may be regulated. In the rear of each of the filling

members 18, and connected with the filling chambers 19, there are ports 45, in which are secured the pipes 44, the pipes 44 being secured and communicating with the interior of the reservoirs 45. Disposed for moving in these reservoirs 45 are floats 46, the floats 46 fitting the sides 47 of the reservoirs. The tops 48 of the reservoirs 45 have openings with collars 49, there around, the collars 49 having inner threads 50 in which mesh the threaded sleeves 51. It will, therefore, be seen that these sleeves 51 may be screwed downward into the reservoirs 45 as may be desired. Secured to the floats 46 there are tubes 52, the tubes 52 extending upward through the sleeves 51, and having lateral openings 53 in close proximity to the floats 46. To the pipes 27 there are secured depending nozzles 54, which are 10 adapted to enter the necks 55 of the bottles when the outlet ports 23 are lowered relatively to the valves 21. Vertical rods 55^a, are secured to the bearing members 56, by the set screws 57, and the positions of the rods 55^a relatively to the bearings 56 may be adjusted as desired. These bearing members 56 are secured to the rods 12 by means of the bolts 58. The lower terminals 60 of the vertical rods 55^a are threaded, and are 20 disposed through openings in the transverse member 59, nuts 61 engaging the threaded terminals 60 of the vertical rods 55^a to support the transverse member 59 on the said vertical rods 55^a. A treadle 62 is connected with the transverse rod 59 by means of which the vertical rods 55^a and with them the transverse member and the filling members 18, may be raised and lowered.

In using the invention, when there is no pressure on the treadle 62, the springs 39^a and 39 hold the filling members 18, with their chambers 19, upward relatively to the valve spindles 29, and the stop 10. When in this position, which is shown in Fig. 2 of the drawings, the head 20, with the inlet port 22, is raised relatively to the valve 32, and the fluid may flow from the pipe 25 into the filling chamber 19, and from thence into the reservoirs 45, and the fluid will continue to flow until the floats 46 strike against the bottom of the sleeves 51. When the floats 46 abut against the bottom of the sleeves 51, it is impossible for further fluid to enter the reservoirs, inasmuch as the lateral openings 53 in the tubes 52, which are the outlets for the air at the top of the reservoirs 45, are disposed within the sleeves 51, and the pressure of the air above the floats 46, in connection with the fact that the floats 46 fit closely the sides 47, of the reservoirs 45, prevents the fluid from continuing to enter the reservoirs 45. When the bottles are in place below the nozzles 54, the treadle is operated, which draws the filling members 18, with their chambers 19 downward relatively

to the valve spindles 29, first to the position shown in Fig. 3 of the drawings, where the inlet ports 22 and the outlet ports 23 are all closed, and then to the position shown in Fig. 4 of the drawings where the filling members 18 with their chambers 19 have moved downward, so that the valves 31 are raised from the outlet ports 23 by the collars 37, and the fluid contained in the filling chambers 19 and in the reservoirs 45 flows out through the outlet ports 23, through the pipes 27, and to the nozzles 54, these nozzles 54 having been lowered with the filling members 18, so that they are disposed in the necks 55 of the bottles, and the fluid flowing through the nozzles will enter the bottles. The quantity of fluid which is permitted to flow into the bottles is regulated by the size of the filling chambers 19 and the capacity of the reservoirs 45, below the floats 46, when the floats 46 are raised and abut against the sleeves 51. By screwing upward or downward the sleeves 51, the quantity of the fluid which the reservoirs 45 will receive may be regulated.

Having thus described my invention I claim as new and desire to secure by Letters Patent:

1. In a filling machine, a filling member having a chamber with a port leading to and a port leading from the chamber, a stop, a valve spindle having one terminal extending into one of the ports with the other terminal disposed for striking the stop when the valve spindle is moved downwardly, two valves mounted on the valve spindle for commanding the ports, a collar secured to the valve spindle between the valves, springs mounted on the valve spindle between the collar and the valves, and a depending nozzle secured to the filling member, with which the port leading from the chamber communicates, so that when the filling member is moved down the spindle will strike the stop, the valves will be operated, and the nozzle will be lowered to a bottle which is to be filled.

2. In a filling machine, a member having a filling chamber, with a port leading to and a port leading from the chamber, a valve spindle extending into one of the ports, two valves mounted on the valve spindle for commanding the ports, a collar secured to the valve spindle between the valves, springs mounted on the valve spindle between the collar and the valves, a nozzle secured to the member for moving with the filling member, there being a passage leading from the outlet port to the nozzle, and means for moving the member relatively to the valve spindle.

3. In a filling machine, a hollow filling member having a bearing and an inlet and an outlet, two heads with ports spaced apart in the member, a valve spindle disposed for

- sliding longitudinally in the bearing, and disposed through one of the ports, three collars secured to the valve spindle, a valve mounted for sliding on the valve spindle between the central collar and one of the outer collars, a second valve mounted for sliding on the valve spindle between the central collar and the other outer collar, springs disposed between the central collar and the valves, and means for moving the filling member relatively to the valve spindle.
4. In a filling machine, a hollow filling member having a bearing and an inlet and an outlet, two heads with ports spaced apart in the member, a valve spindle disposed for sliding longitudinally in the bearing, and disposed through one of the ports, three collars secured to the valve spindle, a valve mounted for sliding on the valve spindle between the central collar and one of the outer collars, a second valve mounted for sliding on the valve spindle between the central collar and the other outer collar, springs mounted on the valve spindle between the central collar and the valves, the other terminal of the valve spindle engaging the stop so that when the first-mentioned member is moved on the standard relatively to the stop the filling member and the heads with the ports will be moved relatively to the valves, a nut on the second-mentioned terminal of the valve spindle, and a spring mounted on the valve spindle between the bearing and the nut for holding the filling member yieldingly relatively to the valve spindle.
5. In a filling machine, a standard, a stop secured to the standard, a member for sliding on the standard, a hollow filling member secured to the first-mentioned member, two heads with ports secured in the filling member, a valve spindle having one terminal disposed through one of the ports, valves mounted on the valve spindle for commanding the ports, the other terminal of the valve spindle engaging the stop so that when the first-mentioned member is moved on the standard relatively to the stop, the filling member and the heads with the ports will be moved relatively to the valves.
6. In a filling machine, a standard, a stop secured to the standard, a member for sliding on the standard, a hollow filling member secured to the first-mentioned member, two heads with ports spaced apart and secured in the filling member, a valve spindle having one terminal disposed through one of the ports, three collars secured to the valve spindle, a valve for commanding one of the ports mounted for sliding on the valve spindle between the central collar and one of the outer collars, a second valve for commanding the other port mounted for sliding on the valve spindle between the central collar and the other outer collar, springs mounted on the valve spindle between the central collar and the valves, the other terminal of the valve spindle engaging the stop so that when the first-mentioned member is moved on the standard relatively to the stop the filling member and the heads with the ports will be moved relatively to the valves.

7. In a filling machine, a standard, a stop secured to the standard, a member for sliding on the standard, a hollow filling member secured to the first-mentioned member having an elongated bearing, two heads with ports spaced apart and secured in the filling member, a valve spindle having one terminal disposed through one of the ports, three collars secured to the valve spindle, a valve for commanding one of the ports mounted for sliding on the valve spindle between the central collar and one of the outer collars, a second valve for commanding the other port mounted for sliding on the valve spindle between the central collar and the other outer collar, springs mounted on the valve spindle between the central collar and the valves, the other terminal of the valve spindle engaging the stop so that when the first-mentioned member is moved on the standard relatively to the stop the filling member and the heads with the ports will be moved relatively to the valves, a nut on the second-mentioned terminal of the valve spindle, and a spring mounted on the valve spindle between the bearing and the nut for holding the filling member yieldingly relatively to the valve spindle.
8. In a filling machine, a standard, a stop secured to the standard, a member for sliding on the standard, a hollow filling member secured to the first-mentioned member having an elongated bearing, two heads with ports spaced apart and secured in the filling member, a valve spindle having one terminal disposed through one of the ports, three collars secured to the valve spindle, a valve for commanding one of the ports mounted for sliding on the valve spindle between the central collar and one of the outer collars, a second valve for commanding the other port mounted for sliding on the valve spindle between the central collar and the other outer collar, springs mounted on the valve spindle between the central collar and the valves, the other terminal of the valve spindle engaging the stop, so that when the first-mentioned member is moved on the standard relatively to the stop the filling member and the heads with the ports will be moved relatively to the valves, a nut on the second-mentioned terminal of the valve spindle, and a spring mounted on the valve spindle between the bearing and the nut for holding the filling member yieldingly relatively to the valve spindle, and a depending nozzle secured to the filling member for feeding fluid to a bottle when the filling member is lowered, one of the ports being in communication with the nozzle.

9. In a filling machine, a hollow filling member having two ports, a valve spindle extending into one of the ports, three collars secured to the valve spindle, a valve mounted for sliding on the valve spindle between

the central collar and one of the outer collars, a second valve mounted for sliding on the valve spindle between the central collar and the other collar, springs mounted on the 5 valve spindle between the central collar and the valves, a reservoir in communication with the filling member between the ports, and having an opening, a float for moving in the reservoir, a sleeve secured in the opening 10 for limiting the movement of the float in the reservoir, and a tube secured to the float and disposed for moving in the sleeve,

there being a lateral opening in the tube, serving as an outlet for the air in the reservoir above the float until the lateral opening 15 is covered by the sleeve.

In testimony whereof I have signed my name to this specification in the presence of two subscribing witnesses.
